INVENTOR,
JACK JENSEN.
By *Donald K. Hippincott*
ATTORNEY.

a disc but very little larger in circumference than the circumference of the completed housing, in contradistinction from the usual method of deep drawing from a large disc which can supply metal to the draw from the periphery, the excess not used being later trimmed off to the desired finished housing size.

No such drawing operation is necessary in forming the housing of my invention, and the reduction in cost effects a marked saving in the production cost of the completed speaker.

15 Another costly production feature is eliminated by the use of my invention, namely the step comprising the usual blanking operation to form the supporting arms, which in the drawn type of housing must be performed after the draw has been completed. Either an extremely complicated and costly die must be made to blank out the spaces between the arms at one operation, 20 or, as is customary, these spaces must be blanked out one at a time, the operator turning the housing on the die to the proper point. These spaces are all blanked out while the stock is flat in the housing herein described, thus still further reducing production costs.

During the process of making the cone housing of my invention, there is no loss of partly finished housings due to irregularities in the metal stock causing tearing during a drawing process. The bending operation by which the arms are extended to form the housing of my invention.

45. *Leucosia* is a genus of *Leucosia* with a worldwide record and a
widely distributed in the tropics. It is a typical genus of the
subfamily *Leucosiinae* and the tribe *Leucosiini*. The genus is
represented by a number of species, including *L. leucosia* (L.) which is
the type species of the genus. The genus is represented by a number of
species, including *L. leucosia* (L.) which is the type species of the genus.

70. *Leptodora* is a genus of aquatic plants, and the name is derived from the Greek words *lepto* (thin) and *dora* (leaf). The leaves are thin and delicate, and the plants are often found in shallow water or on the margins of ponds and streams. The genus includes several species, such as *L. heterophylla* and *L. pyramidalis*.

vention does not strain the metal sufficiently to cause such loss, and the rejection of partly finished housings is therefore practically eliminated.

I claim:

1. A cone housing for a sound reproducer comprising a disc having portions removed from the interior thereof to form an outer rim and a plurality of inwardly radiating arms, said arms being bent adjacent their junction with said rim to form supporting feet for said rim.

2. A cone housing for a sound reproducer comprising a disc having portions removed from the interior thereof to form a rim and a plurality of inwardly radiating arms, said arms being outwardly bent to describe a cone and formed at their ends into feet whereby said housing can be mounted on said sound reproducer.

3. In a loud speaker having a substantially cone shaped diaphragm and an actuating motor attached thereto, means for supporting the rim of said diaphragm which comprises a disc having portions removed from the interior thereof to form a peripheral shelf on which said rim may rest, and a plurality of inwardly radiating arms, said arms being bent adjacent said junction with said rim to form an enclosure for said cone, and fastened at their free ends to said actuating motor thereby positioning said cone in proper operating relationship with said motor. 95 100
